UNITED STATES PATENT OFFICE.

GEORGE L. NAUMANN, OF ST. LOUIS, MISSOURI, ASSIGNOR OF ONE-THIRD TO WILLIAM F. RILEY AND ONE-THIRD TO HUBERT CRADOCK, BOTH OF ST. LOUIS, MISSOURI.

DITCHING-MACHINE.

1,100,604.

Specification of Letters Patent. Patented June 16, 1914.

Application filed May 26, 1913. Serial No. 770,040.

To all whom it may concern:

Be it known that I, GEORGE L. NAUMANN, a citizen of the United States, residing in St. Louis and State of Missouri, have invented certain new and useful Improvements in Ditching-Machines, of which the following is a specification.

My invention relates generally to machines utilized for digging ditches or 10 trenches, and more particularly to an attachment for such machines whereby the excavated earth is delivered onto an endless conveyer and carried thereby back into the ditch or trench for the purpose of filling the 15 same and covering the pipe or tile which is laid in the bottom of said ditch or trench.

The principal object of my invention is to combine with an ordinary and well known 20 form of ditching or trenching machine an endless conveyer preferably in the form of a belt which extends a substantial distance away from the machine so that the dirt taken from the ditch or trench by the digging buckets can be readily carried back and 25 deposited in the ditch or trench upon the pipe laid therein, thus economically re-filling the ditch or trench with the dirt taken therefrom.

Further objects of my invention are to 30 provide simple means for driving the conveyer, which carries the dirt back into the ditch, and to provide a simple support for the outer portion of the frame-work upon which the endless conveyer operates.

With the above and other objects in view, 35 my invention consists in certain novel features of construction and arrangement of parts hereinafter more fully described, claimed and shown in the accompanying 40 drawings in which—

Figure 1, is a plan view of a portion of an ordinary ditching machine and showing my improvement combined therewith. Fig. 2, 45 is a side elevational view of the parts seen in Fig. 1, with a portion of the ditch or trench shown in vertical section. Fig. 3, is an enlarged horizontal sectional view taken approximately on the line 3—3 of Fig. 2 and showing the driving-shaft of the endless 50 conveyer. Fig. 4, is an enlarged side elevational view showing the driving connections from the driving shaft of the ditching machine to the driving shaft of the endless

conveyer. Fig. 5, is a transverse sectional view taken approximately on the line 5—5 of Fig. 4.

Referring by numerals to the accompanying drawings, 10 designates the frame-work of an ordinary ditching or trenching machine, the rear portion of which framework 55 is supported by a traction device commonly known as a "caterpillar". Arranged at the end of the ditching machine is a trenching arm 11 upon which operate endless chains 12 carrying buckets 13, the same being provided 60 with digging teeth. Journaled for rotation in suitable bearings on the framework 10 is a transversely disposed driving shaft 14, which is operated directly from the engine 65 of the machine and fixed on one end of this shaft is a pinion 15 which meshes with a large gear wheel 16, the same being mounted on a transversely disposed shaft 17. This shaft 17 carries the sprocket wheels upon 70 which the chains 12 operate. Arranged for 75 operation on suitable rolling supports at the rear end of the ditching machine and beneath the conveyer comprising the chains 12 and buckets 13 is a transversely disposed belt conveyer 18, the same being driven in 80 any suitable manner. This conveyer receives the dirt which is carried up out of the trench by the buckets 13 and delivers said dirt to the side of the machine. The parts 85 just described are of ordinary well known construction and form no part of my invention.

Detachably connected in any suitable manner to one side of the end of the ditching machine is an elongated frame or arm 90 19, the same being reinforced or stayed in any suitable manner, and arranged in the end of this arm immediately adjacent to the machine is a transversely disposed shaft 20 the inner end of which is connected by a universal joint 21 to a shaft 22 which latter is journaled in suitable bearings on the frame 10 of the machine. Arranged immediately above this shaft 22 is a second shaft 23, the same carrying a pinion 24 which meshes 95 with a pinion 25 on the shaft 22. Arranged on the frame 10 and operating in suitable bearings is a shaft 26, on one end of which is fixed a gear wheel 27 which meshes with the large gear wheel 16 and carried by this 100 shaft 26 is a sprocket wheel 28, which 105

ceives a sprocket chain 29, the latter operating upon a sprocket wheel 30, which is fixed on the shaft 23.

The driving connections just described 5 provide means for driving the shaft 20, which latter carries a drum or roller 31, the same being arranged within the arm 19. Operating upon this drum or roller 31 and passing over and beneath the arm 19 is an 10 endless conveyer 32, the same operating around a drum or roller 33, which latter is preferably located in adjustable bearings at the outer end of said arm 19. Idle rollers 34 are arranged at suitable distances apart 15 in the upper portion of the arm 19, said rollers being for the purpose of supporting the endless carrier 32, as it passes over said arm. The underrunning portion of the conveyer is supported by idle rollers 35 arranged at suitable distances apart on the 20 underside of the arm 19. Arranged at the sides of the arm 19 and slightly above the top thereof, are rails 36 which are supported in any suitable manner from said arm, said 25 rails being for the purpose of preventing the dirt from dropping off the endless conveyer as it is carried thereby to the outer end of the arm.

Arranged immediately over the end of 30 the arm 19, which is connected to the ditching machine, is a suitable framework 37 and journaled in suitable bearings at the ends thereof, are shafts 38 and 39, the latter being provided with a sprocket wheel 35 40 which receives the sprocket chain 41 and this sprocket chain passes around a sprocket wheel 42 that is fixed on the outer end of the shaft 20.

Operating upon suitable drums carried 40 by the shafts 38 and 39 is an endless conveyer 43, the central portion of which is supported by suitable idle rollers and the rear portion of this conveyer is positioned directly beneath the outer end of the trans- 45 verse conveyer 18. While in use, the outer end of the arm 19 and the endless conveyer operating thereon is supported by upright members or legs 44, the lower ends of which are provided with caster wheels 45 which 50 engage on short rail sections 46, the same being supported in any suitable manner, preferably by means of a platform 47 which is laid directly upon transverse rails 48, the same being positioned across the ditch or 55 trench formed by the machine.

The operation is as follows: Rotary motion from the driving shaft 14 is transmitted to shaft 26 through gears 15, 16 and 27 and from thence to shaft 22 through sprocket 60 chain 29 and pinions 24 and 25. Shaft 22 drives shaft 20 and thus the endless conveyer 32 is caused to move lengthwise over the arm 19. Rotary motion of the shaft 20 is transmitted to shaft 39 through sprocket 65 chain 41, thus operating the endless con-

veyer 43. The buckets 13 carry the dirt up out of the trench and deliver said dirt onto the transverse conveyer 18, by which said dirt is delivered onto the endless conveyer 43 and which latter delivers onto the inner 70 end of conveyer 32. The arm 19 being of considerable length provides for the delivery of the excavated earth back into the trench, a considerable distance to the rear of the ditching machine.

It will be understood that the machine moves forward in its work very slowly and as the trench is formed by the digging buckets 13, workmen follow along and place pipe or tile in the trench immediately behind the lower end of the trenching arm. The arm 19 and conveyer thereon extend a considerable distance beyond this trenching arm, and consequently the excavated dirt is carried back a sufficient distance to be 85 filled in the trench over the pipe laid therein.

Heretofore it has been the practice to deliver the excavated dirt alongside the trench formed by the machine and this dirt was afterward shoveled into the trench, but by 90 my improved construction the excavated earth is delivered back into the trench on top of the pipe therein without extra labor and with the expenditure of but comparatively little power.

My improved refilling attachment is comparatively simple, comprises a minimum number of parts, can be readily combined with ordinary forms of ditching and trenching machines, can be operated with little 100 power, and provides efficient means for economically filling trenches after the pipe or tile has been placed therein.

It will be readily understood that minor changes in the size, form and construction 105 of the various parts of my improved attachment for ditching machines can be made and substituted for those herein shown and described without departing from the spirit of my invention, the scope of which is set 110 forth in the appended claims.

I claim—

1. The combination with a ditching machine, having a transversely disposed conveyer at its rear end to receive the dirt 115 taken out of the ditch by the machine, of an elongated frame connected to one side of the machine at its rear end, an endless conveyer arranged for operation lengthwise on said frame, an intermediate endless conveyer interposed between the transverse conveyer of the machine, and the conveyer operating on said frame, and means for simultaneously operating the intermediate conveyer and the conveyer on the frame.

2. The combination with a ditching machine, of an elongated frame connected to and projecting rearwardly from one side of the machine, an endless conveyer arranged for operation on said frame, a framework 130

arranged above the inner end of said frame, a short endless conveyer arranged for operation in said framework, for delivering dirt elevated by the ditching machine onto the 5 endless conveyer operating on the elongated frame, and means for simultaneously driving said endless conveyers.

3. An attachment for ditching machines comprising a framework applied to the rear 10 end of the machine, an endless conveyer arranged for operation within said framework for receiving dirt elevated by said machine, an elongated frame adapted to be connected to the ditching machine and to

extend rearwardly therefrom, the inner end 15 of which frame is arranged beneath the first mentioned framework, an endless conveyer arranged for operation on the elongated frame, and means for simultaneously driving said endless conveyers. 20

In testimony whereof I hereunto affix my signature in the presence of two witnesses, this 21st day of May, 1913.

GEORGE L. NAUMANN.
